CHARLES F. RICHARDSON, OF WOONSOCKET, RHODE ISLAND, ASSIGNOR TO KARPELES COMPANY, OF PROVIDENCE, RHODE ISLAND, A CORPORATION OF RHODE ISLAND.

SORTING MACHINE.

Application filed October 1, 1921. Serial No. 504,679.

To all whom it may concern:

Be it known that I, CHARLES F. RICHARDSON, a citizen of the United States, residing at Woonsocket, in the county of Providence and State of Rhode Island, have invented certain new and useful Improvements in Sorting Machines, of which the following is a specification.

This invention relates to machines for sorting granular material according to the size of the grains and has particular reference to devices of this type wherein the unassorted material is fed from a common source through a series of sorting stations at each of which grains of a given size are retained, the progress of the material being such that as the latter passes through the machine the charges from station to station become progressively smaller in size as to grains. The charges retained at the several stations may be collected in separate containers and removed from the machine.

The present invention is designed more particularly for assorting such commodities as artificial pearls, nuts or fruits for example; and the apparatus embodies certain novel features of construction and arrangement of parts adapted to carry out the necessary sequence of operations to produce the desired result.

In machines of this general type as now constructed, it is usually necessary to make substantial alterations in the various parts of the machine if it is desired to change one set of sorting or sizing members for another set having different sized sorting openings. By my invention I provide a simple and efficient mechanism to accomplish this purpose without changing any of the operative parts of the machine and I can by a very simple operation, adapt the machine to separate practically any number of the various sizes of material, and one object of the invention is to provide means whereby this purpose is attained.

A further object of my invention is to provide a feeding mechanism adapted to deliver charges from a general hopper at predetermined intervals according to the positions of the sorting stations into which the charge is conducted.

An illustrative embodiment of the invention incorporated in a machine specially designed to sort batches of artificial pearls is

shown in the accompanying drawings, in which—

Fig. 1 is a front elevational view of a machine embodying the invention, parts being broken away;

Fig. 2 is an enlarged view of the upper or receiving portion of the machine, certain parts appearing partly in section and others in elevation;

Fig. 3 is an enlarged view of the lower or drive portion of the machine, parts being broken away to clearly show internal mechanism;

Fig. 4 is a side elevational view looking in the direction of the arrow 4 of Fig. 2, showing the automatically controlled clutch mechanism for controlling the operation of the conveyor;

Fig. 5 is a perspective view of the supporting, tilting and driving mechanism for a screen or trommel;

Fig. 6 is a perspective view of one of the receiving receptacles showing the projecting chute and cam surfaces for opening a trap door carried by the trommel for the purpose of releasing the contents during the tilting operation;

Fig. 7 is a substantially transverse sectional view through one of the sorting units illustrating the means used to release any body which may have become engaged in the perforations in the screens.

Referring to the drawings, 10 denotes the machine frame comprising a pair of vertical side walls 11 secured at their lower ends to a base or platform 12 and spaced apart at their upper ends and secured to the opposite edges of an overhead piece 13. The rear of the frame 10 is formed by a wall or plate 14 which supports, at various points thereon, the operating mechanism of the device. The platform 12 supports a motor 15 having its drive shaft 16 provided with a worm 17. This motor 15 is preferably located in the lower left hand corner of the frame 10, as shown in Figures 1 and 3, and is secured thereto by suitable brackets 18.

Power is transmitted from the worm 17 to a worm wheel 19 meshing with the screw and mounted on one end of a counter shaft 20 adapted to rotate in suitable bearings 21 secured to the back wall 14. With this construction the speed of the counter shaft 20 is substantially decreased relatively to the

speed of the motor shaft 16. A bevel gear 22 is carried by the opposite end of the counter shaft 20 and is in mesh with a similar bevel gear 23 mounted on one end of a 5 drive shaft 24 which is supported in bearings 25 secured to the back wall 14 and which extends substantially parallel to the wall itself. As the shaft 24 revolves the sorting, tilting and feeding mechanisms are 10 caused to operate in a manner hereafter described.

The sizing or sorting mechanism, which will now be described, is shown in detail in Figures 1, 2, 3 and 5. Mounted on the 15 drive shaft 24 intermediate its ends is a bevel gear 26 in mesh with a similar bevel gear 27 carried by a counter shaft 28 which in turn carries a sprocket wheel 29 and which is loosely supported in a bearing provided in the back wall 14. Passing over the sprocket wheel 29 is a continuous chain 30 which travels in the direction indicated by the arrows *a* in Figures 1, 2 and 3. Extending upwardly from the sprocket wheel 25 29, the chain 30 engages alternate sides of a series of sprocket wheels 31 arranged one above the other and in parallel vertical alignment with the upright side walls 11. These sprockets are equidistantly spaced 30 apart and are mounted on stud shafts 32 bearing in suitable openings provided in the back wall 14. The chain 30 extends from next to the uppermost sprocket wheel 31 towards the left side of the frame 10 closely adjacent the side wall 11 and engages 35 about a sprocket wheel 33 which drives the feeding mechanism. The chain 30 then extends to the uppermost sprocket wheel 31 and passes to an idler sprocket wheel 34 40 loosely mounted on a stud shaft fixed in the back wall 14. This idler sprocket wheel 34, which constitutes the uppermost support for the chain, is directly above and in line with the sprocket wheel 29 so that the 45 chain 30 extends in a vertical plane from the one sprocket to the other.

As shown in Figure 5, each stud shaft 32 projects substantially beyond its sprocket wheel 31 and carries intermediately thereof 50 a rocking sleeve 35 having a laterally projecting arm 36 adapted to support one end of a trommel or substantially cylindrical screen A, the other end of which is removably secured to the flanged end portion of a 55 bevel gear 37 meshing with a similar bevel gear 38 carried on the outer end of the stud shaft 32 beyond the sleeve 35. It will be noted that all of the sorting devices are constructed and mounted in exactly the same 60 way, except that the cylinders, of which there are two series, one at the right hand side and the other at the left hand side of the frame 10, are arranged so that the members of the right hand series are on a substantially 65 higher horizontal plane than the cor-

responding members of the left hand series. This staggered relation of the cylinders causes the material to be sorted to travel by gravity from the uppermost members to the lowermost members in a zigzag line. It will 70 also be noted that the perforations or mesh in the revolving cylinders A will be largest in the uppermost member and gradually diminish in size in each successive cylinder so that the smallest openings will be in the 75 lowermost member.

Referring again to Figure 5 the projecting arm 36 comprises a substantially straight rigid bar carrying, at a point adjacent the sleeve 35, a bracket 39 to support the bevel gear 37 in a bearing collar 40 through which the flanged portion 41 of the gear itself projects. The flanged portion 41 consists of an annular inner portion 42, the face of which is secured to the rear face of the bevel gear 37 by machine screws projecting through the gear proper and received in threaded openings in the ring 42, and an integral marginal flange 43 projecting outwardly from the periphery of the ring 42. This flange 43 is substantially a narrow gauge web designed to provide a shoulder, at the side thereof opposite to the ring portion 42, and against which the end of the cylinder screen A may rest, as shown in the sectional view of one 95 of these cylinders in Figure 2; the annular portion 44 which projects beyond the flange 43, and which is substantially of the same size as the diameter of the inner periphery of the cylinder screen A, is used as a centering 100 device for one end of the cylinder A. In order to compel the cylinder screen A to revolve with the bevel gear 37 and flanged portion 41 I provide the shoulder of the web 105 43 with a pair of diametrically opposite pins 45 projecting outwardly over the surface of the centering ring 44. These pins 45 register with correspondingly located openings 46 in the end of the cylinder A. Extending axially through the bevel gear 37 and flange 41 is a receiving or intake opening 47 having its inner annular wall flared outwardly from 110 a point midway of the width of the flanged portion 41 to the face of the annular centering ring 44.

The mechanism just described is the supporting and operating means for the cylinder screens A at one end thereof the opposite end being capped by a cup shaped member 48 having a pair of discharge openings 49 and a centrally disposed conical bearing 50 adapted to receive an adjustable cone bearing pin 51 carried adjacent the outer end of a pivoted arm 52. This arm 52 is substantially L-shaped, the longer branch carrying a U-piece 53 having one of its edges held parallel to the axis of the cylinder screen A and the other edge projecting at substantially right angles to the first named edge. A pivot screw 54 extends 115 120 125 130 135

through the U-piece 53 and through an opening in the free end of the arm 36. The set positions of pivoted arm are 52 determined by a flat spring 55 secured at one end 5 to the rear face of the arm 36 and extending forwardly from a slight offset to engage one of the edges of the U-piece 53, as shown in Figure 5. The shorter branch of the L-shaped arm 52 projects downwardly to a 10 point substantially below the bearing pin 51 and carries a laterally disposed plate 56 to which is secured one member of a hinge 57 supporting a trap door 58. This door is normally held against the discharge end of 15 the cylinder A by a coiled spring 59, and the lower portion extending below the periphery of the cylinder is bent outwardly away from the latter and provided with a lip 60 adapted to engage cam surfaces to 20 open the door 58 when the cylinder is tilted to the discharge position. Mounted on the forward surface of the arm 36 and projecting outwardly towards the free end thereof to a point slightly short of the operating 25 position of the pivoted arm 52 is the projected portion of a shield 61 which spans the body portion of the cylinder A transversely of its axis. This shield 61 is substantially arch shaped, its crown portion 30 being of considerable width and projecting below the periphery of the cylinder screen. The conveying chutes 52 are best illustrated in Figure 5, wherein the shields 61 are shown carried by the arm 52 so as to 35 move relatively to said chutes and transversely thereof to enclose the rear open ends of the latter against escape of their contents. The chute is substantially semi-cylindrical and is spaced away from the periphery of 40 the cylinder screen and rigidly secured to suitable pivoted brackets 63 projecting from the back wall 14. The chute proper extends the full length of a cylinder and projects forwardly toward the opposite series of 45 cylinders and into the interior of the next lower cylinder through opening 47. The brackets 63 support the rear ends of the chutes, the forward end of each chute being supported in automatically adjustable relation 50 to the mouth of the opening 47 in the succeeding lower cylinder A by means of a yoke 64 projecting outwardly from the collar 40 and upwardly over the bevel gear 37 to receive the discharge end of the chute 62. 55 It will be noted with reference to Figure 2, that the portion of the bracket 63, to which the rear end of the chute is secured, is pivotally mounted, so that as the yoke 64 is moved arcuately with the cylinder A, as 60 hereinafter described, the tendency will be to incline the discharge end of the chute 62 upwardly, while the contents of the cylinder A which is being inclined downwardly towards the discharge end, will escape 65 through the opening 49, and thereby avoid

the possibility of undersized pearls passing directly into the receiving receptacles.

The tilting apparatus, shown in Figures 3 and 5, is controlled and operated from the drive shaft 24 which carries a pair of worms 65 and 66 meshing with worm wheels 67 and 68 mounted on suitable bearing shafts projecting from the right and left hand sides, respectively, of the back wall 14. It will be seen that while the rotary movement of the staggered cylinders A is controlled and operated from the single continuous chain 30 the tilting or discharging mechanism is divided so that the cylinders on the right of the frame 10 are rocked by the operation of the worm screw 65 and the cylinders on the left of the frame are rocked by the operation of the worm screw 66. Rotating with the worm wheels 67 and 68 and secured to the latter are sprocket wheels 69 and 70 respectively, over which pass continuous chains 71 and 72. These chains travel in the directions of the arrows b and engage alternate sides of a series of sprockets 73 keyed to stud shafts 74 journaled and supported in suitable bearings in the back wall 14. These chains having traveled beyond the uppermost sprockets 73 pass to idler sprocket wheels 74 and 75 the latter being substantially in vertical alignment with the sprockets 69 and 70 respectively, so that the returning portions of the chains 71 and 72 will be substantially parallel with the side walls 11. The inwardly extending portions of the stud shafts 74 cross beneath the central portions of the rocker arms 36 and are provided with adjustable heart shaped cams 76 adapted to contact with cam rollers 77 loosely mounted on the lower ends of downwardly projecting lugs 78 which form integral parts of the rocker arms 36. The relative positions of these cams 76 may be adjusted so that the rocker arms 36 may be raised to tilt the cylinder screens A immediately after they have received their charges, but the greatest efficiency of operation has been obtained by arranging the cams, as shown in Figure 1. Before explaining the positions of these cams 76 it might be noted that due to the chains 71 and 72 engaging alternate sides of the sprockets 73 and thereby alternating the direction of rotation of each sprocket, it has been found necessary to reverse alternate cams. The purpose of having the chains 71 and 72 engage the sprockets 73 in this manner is to hold the chains taut against the sprockets without the use of chain tightening idlers. Referring again to the relative positions of the cams 76, as illustrated in Figure 1, the high point of the uppermost cam 76 on the right hand side of the frame 10 is directly beneath the cam roller 77 thereby holding the discharge end of the cylinder screen A above the lever of 11

the receiving end of the latter. The cam 76 at the top of the left hand series is set so that its high point has passed the roller 77 a very slight distance and inasmuch as this cam revolves towards the right the roller 77 is shown as descending the left side of the cam. This arrangement calls for a slight advance in the setting of each succeeding cam starting from the uppermost 10 and then alternately from right to left and left to right across the frame 10 so that by the time the lowermost cylinder A has been tilted rearwardly to discharge its contents the uppermost cylinder will have returned 15 to its initial or receiving position.

The feeding mechanism, shown in Figure 2, comprises a hopper 80 mounted adjacent the left hand edge of the machine and resting over a suitable opening in the over head piece 13. The mouth of the hopper is a restricted opening 81 at the lower end of an inclined portion of the hopper itself and is provided with an undercut portion 82 adapted to receive the intake end of a conveyor 20 casing 89. The conveyor comprises a cast head 84 provided with the intake tubular portion, referred to above, which is substantially upright and leads to an opening 85 adjacent the bottom of the casting and 25 at right angles to the axis of the upright portion. The portion of the wall which is opposite the opening 85 is provided with a bearing opening 86 to support one end of a shaft 87, the opposite end of which carries a screw conveyor 88. Secured at one end to the casting 83 and projecting axially of the shaft 87 is a cylindrical casing 89 enclosing the screw conveyor 88, the other end of said 30 casing being provided with a cap 90 having a bearing opening therein to receive the end of the shaft 87 beyond the screw conveyor. Pivoted to opposite sides of this cap 90 and projecting outwardly therefrom is a chute 91 leading from a discharge opening 93 in 35 the end of the cap. The forward end of the chute is yieldably supported in the forked piece 64 of the uppermost cylinder screen A. The casting 84 is provided with an integral bracket 94, shown in Figure 4, which 40 is secured to the back wall 14 and includes a second bearing bracket 95 the bore of which extends at an angle to the axis of the shaft 87, and which is substantially on the same plane as the latter. A bevel gear 96 45 is keyed to the shaft 87 and is in mesh with a similar bevel gear 97 carried by a hollow shaft 99 loosely mounted in the bearing 95. The hollow shaft 99 extends rearwardly of the machine and is provided with a key 100 50 in its outer periphery and adjacent the end thereof to receive a keyway 101 of the movable member of a toothed clutch 102 adapted to slide axially of the hollow shaft 99. Loosely mounted in the bore of this hollow 55 shaft 99 and projecting to a point closely

adjacent the back wall 14 is a constantly rotating shaft 103 supported at a point short of the rear end thereof in a bearing 104 carried by the back wall 14. Pinned to the shaft 103 adjacent the rearward end of the hollow shaft 99 is the second member 70 of the clutch 102. Power is applied to the shaft 103 through a spur gear 105 pinned to the rearward end of shaft itself beyond the bearing 104, and meshing with a substantially larger spur gear 106 carried by shaft 107 on the opposite end of which is keyed the sprocket wheel 33. 75

The mechanism just described provides a means for constantly rotating the shaft 103 80 and one member of the clutch 102, and in order to synchronize the tilting operation of the uppermost cylinder A with the rotation of the screw conveyor 88 the members of the clutch 102 must be brought into engagement 85 with each other after the cylinder has been returned to its initial position. The movable member of the clutch 102 is provided with an annular groove 108, in its outer periphery, to receive a yoke 109 of a bell crank 90 lever 110 which is pivoted about a pin 111 carried by a portion of the bracket 94. The other arm of the lever 110 pivotally supports one end of a link 112 the opposite end of which projects downwardly below the plane of the rocker arm 36 and is pivoted to one end of a straight lever 113 the latter being pivoted midway of its length to the back wall 14. The opposite end of the lever 113 is normally pulled downwardly by a spring 113^a and carries a cam roller 114 adapted to rest on a rotary cam 115, which is mounted on the stud shaft 74 and which, as shown in Figure 5, forms an integral 100 part of the uppermost cam 76 of the left hand series. This cam 115 is virtually a segment of a perfect round disk and is provided with a quick rise and fall to and from the high portion of the cam. In Figure 2, the relative positions of the cams 76 and 105 115 are shown, whereby the rise to the cam 115 effecting the operation of the clutch 102 to throw the latter into engagement is operating substantially simultaneously with the continued raising movement of the roller 77 after the latter has been lifted over the first rise in the cam 76 of the uppermost right hand cylinder screen A to return the latter to the receiving position. The length of the operating cam surface of the cam 115 corresponds to the length of the second rise 76^a of the cam 76. 110

The receiving stations at the discharge 115 ends of the cylinder screens A are best shown in Figures 2, 3 and 6, and consist of rectangular boxes 116 supported in suitable box like brackets 117 secured to the inner face of the side walls 11. Each of these receptacles 116 is provided with a cut out portion 118 extending from the upper open edge of the 120 130

front wall to a point about one half the height of the latter and midway the length of the wall. Projecting outwardly from the edges of the cut out portion 118 and inclined upwardly is a chute 119 the upper free end of which is flared outwardly to a width substantially equal to the diameter of the cylinder screen A from which the sorted charge escapes and falls upon the chute. When in operative position the lip 60 of the trap door 58 is directly over the central portion of the chute 119 and is adapted to contact with a pair of upright cam surfaces 120 mounted centrally of the chute so that as the cylinder 15 A is tilted downwardly at its discharge end the lip 60 will ride over the cams 120 away from the end of the cylinder thereby causing the door 58 to swing about its hinge and away from the discharge opening 49 in the cap 48.

The cylinder screens may be constructed of any suitable material such as wire mesh or perforated metal plates in the form of tubes, the latter being of any length and diameter consistent with the type of material to be sorted, but for illustrative purposes I have shown a series of perforated shells 121 of substantially identical construction except that the perforations in the uppermost shell 30 are the largest and graduate in size in each succeeding shell until the smallest openings are in the lowermost shell.

In Figure 3, the final receiving station or receptacle is shown and comprises a box 122 removably supported on suitable brackets 123 secured to the back wall 14. Into this receptacle all of the material too small to be retained in the lowermost cylinder is collected. As hereinafter explained this unsorted material may be sized in another set of cylinders having still smaller openings than those of the machine through which the material passed.

To prevent pieces of the material being sorted from remaining wedged between the edges of the perforations of the cylindrical casing 121 I provide a wiper 124, shown in Figure 7, which consists of a slightly flexible piece of material of a length equal to that of the cylinder itself and which is adapted to be rigidly held along one of its edges by two clamping members 125 carried on the inner edge of the rocking arm 36. The opposite edge of this member 124 projects outwardly toward the periphery of the cylinder where it contacts with and follows the contour of the latter. With this construction it will be seen that should a particle of the material be of a size which will very closely fit the diameter of the perforations and become wedged therein the wiper 124 will push the particle backwards into cylindrical shell 121.

The following is a sequence of steps which constitute one cycle of the operation of the machine. Assuming the hopper 80 to have

been filled with the material to be sorted, pearls for example, the cylinder screens A in their respective positions according to the cams 76, shown in Figure 1, and the superposed receiving receptacles 116 in proper positions, and assuming further that the power is turned on, the driving shaft 24 will rotate causing the chains 30, 70 and 71 to travel in the directions of the arrows *a* and *b* to impart a continuous rotary and an intermittent oscillatory movement to each cylinder and to feed predetermined quantities of such material from the hopper 80 at certain intervals and into the interior of the uppermost cylinder screen for separation.

The operation of the feeding mechanism is as follows:—Taking the position of the cam 115, shown in Figure 2, which is rotated in clockwise direction, the drop in the cam 115 is lowering the roller 114 of the arm 113 under the tension of the spring 113a. The link 112 is moving upwardly rocking the bell crank 109 and releasing the clutch members from engagement with each other.

The roller 114 having reached the low portion of the cam 115 will have completely released the clutch 102 and the conveyor screw 88 will then be brought to rest. At this stage in the operation the material has been conveyed from the inlet opening 85 at the base of the hopper to the discharge opening 93 in the end of the conveyor casing 89. From the discharge opening 93 the material falls upon the inclined chute 91 and descends into the interior of the cylinder shell 121. It will be understood that the cylinder A of each series are constantly rotating so that immediately a charge of material is received the separating operation is effected and the particle smaller than the perforations in the cylinder in which they are conducted fall to the underlying chute 62 and so on until the very smallest particles are collected in the lowermost receptacle.

Subsequently to the releasing movement of the clutch members 102 by the cam 115, the rotary movement of the cam 76 operating the uppermost right hand cylinder A has brought the fall in the last named cam just in advance of the roller 77 so that as the cam 76 continues further rotation the roller and the rocker arm 36 will have moved arcuately and in a downwardly direction about the stud shaft 32 to discharge the separated material in the cylinder. As the discharge end of the cylinder approaches its extreme lowermost position the lip 60 on the trap door 58 contacts with the cam surfaces 120 and tends to swing the former outwardly away from the openings 49. In this tilted position all of the retained material within the cylinder A escapes through the discharge opening 49 onto the chute 119 and into the receptacle or box 116. This operation takes place in each of the staggered sorting sta-

tions of the machine and at subsequent periods, because as the remaining portion of a charge travels from one station to the next lower station several rotations of each cylinder are necessary to properly separate the smaller sizes from the size unable to escape through the perforations. And in order to follow up with a subsequent charge simultaneously with the discharge of the preceding charge from the lowermost cylinder the cams 76 are adjusted so that each lags slightly behind the preceding one; or in other words, the rise in the uppermost cam 76 of the one series moves against the roller 77 slightly in advance of the uppermost cam 76 of the other series and so on down from side to side until the fall in the lowermost cam is about to discharge the contents of its cylinder while the rise in the cam of the uppermost cylinder is lifting the latter to its initial position to receive a new charge.

In order to explain the operation necessary to make a rapid change of one set of cylinders for another set having different size perforations, particular attention is called to Figure 5. The operations necessary are as follows:—In removing a cylinder screen A the L-shaped arm 52 is swung about its pivot screw 54 until the flat side of the U piece 53 extending substantially parallel to the long arm of the member 52 is parallel with the spring 55. The arm 52 will then remain in this position until the cylinder has been moved axially and away from the flange 44 and pins 45 of the bevel gear 37. A new cylinder is then substituted for the other by inserting its open end over the flange 44 and bringing the openings 46 into register with the pins 45 and then seating the end of the cylindrical casing 121 against the web or shoulder 43. The arm 52 is then returned to its initial position and the pin 51 centered in the bearing 50 of the discharge end or cap 48 of the casing 121.

Having thus described my invention, what I claim and desire to secure by Letters Patent is:—

1. In a machine for sorting material according to size, the combination of a plurality of cylindrical sorting stations, means for operating said stations, and oscillating means for collecting unsorted material from the stations and delivering same for subsequent separation to succeeding stations.
2. In a machine for sorting material according to size, the combination of a plurality of cylindrical sorting stations, said stations being disposed one above the other and at opposite sides of the machine, means for operating said stations, and oscillating means for collecting the unsorted material from the stations and delivering same for subsequent separation to the succeeding lower stations at the opposite sides of the machine.

3. In a machine for sorting material according to size, the combination with a feeding mechanism, of a plurality of cylindrical sorting stations, said stations being disposed one above the other at alternate sides of the machine, means for operating said feeding mechanism and said stations, and oscillating means for collecting unsorted material from the stations and delivering same to the succeeding stations at the opposite sides of the machine.

4. In a machine for sorting material according to size, the combination with a feeding mechanism for feeding charges of said material to be separated, of a plurality of sorting stations comprising cylindrical screening devices arranged in series at opposite sides of the machine, the screening devices of one series being disposed at a different plane from the corresponding screening devices of the other series, means for continuously rotating and intermittently oscillating said screening devices and operating said feeding mechanism, and oscillating means for collecting the unsorted material for subsequent separation from each screening device and delivering same to the interior of the succeeding lower screening device of the opposite series.

5. In a machine for sorting material according to size, the combination with a feeding mechanism for feeding charges of said material, of a plurality of cylindrical revolving and intermittently oscillating sorting stations for receiving said charges for subsequent separation, means for operating said stations, oscillating means for conveying the remaining portion of said charge from one station to another station, and means for receiving the retained portion of said charge at each station.

6. In a machine for sorting material according to size, the combination of a plurality of sorting stations comprising cylindrical screening members provided with inlet and outlet openings at opposite ends thereof, pivotal supporting members for said screening members, means for continuously rotating said screens, and means for operating said supporting members to incline the axis of said screening members first in an upwardly direction toward the outlet ends and then in a downwardly direction toward the same ends.

7. In a machine for sorting material according to size, the combination of a plurality of sorting stations comprising perforated cylindrical members, a supporting apparatus for each cylindrical member, including means whereby a portion of said apparatus may be adjusted to remove said cylindrical member, and means for imparting continuous rotary movement to said cylindrical members and intermittent oscillatory movement to said supporting apparatus.

8. In a machine of the character described, the combination of a plurality of sorting stations, each of said stations being provided with a perforated cylinder having in-
5 let and outlet openings at opposite ends thereof, a pivoted supporting arm adapted to support opposite ends of said cylinder, a cam for oscillating the free end of said arm relative to its pivot, and means for continuously rotating said cylinder and said cam.
9. In a machine of the character described, the combination of a plurality of sorting stations arranged in series at opposite sides of the machine, the members of
15 one series being located on a plane above the plane of the members of the other series, a plurality of supporting members for said sorting stations including pivoted arms provided with fixed bearings at one end and
20 adjustable bearings at the opposite end thereof, operating means including continuously rotating adjustable cams adapted to move said supporting arms arcuately about their pivots, means removably mounted in
25 the bearings of said arms for receiving retaining and separating the material to be sorted, and operating means actuated by the arcuate movement of said supporting arms whereby the retained contents of said
30 means carried by said arms may be discharged adjacent sorting stations.
10. In a machine of the character described, the combination of a plurality of sorting stations having continuously rotat-
35 ing perforated cylinders, pivoted supporting means for each cylinder including a fixed bearing adjacent the pivoted end thereof, an adjustable arm at the opposite end of said supporting means and having a bearing portion adjacent its free end, a spring actuated member carried by said adjustable arm and adapted to enclose one end of said cylinder, a receptacle for each cylinder, and means carried by said receptacle for operating said enclosing member substantially simultaneously with the move-
40 ment of said pivoted supporting means in one direction and to release the contents of said cylinder to escape into the receptacle.
- 45 11. In a machine of the character described, the combination of a plurality of pivotally supported sorting stations comprising cylindrical screens arranged in series at opposite sides of the machine, the stations of one series being disposed above the corresponding stations of the other series, a series of driving means mounted axially of the pivotal supports of said sorting stations, means for rotating alternate members of said driving series in opposite directions, and means carried by said sorting stations adapted to engage said driving means whereby the former may be rotated at any inclination and in the same direction.
- 50 12. In a machine of the character de-
scribed, the combination of oppositely dis-
posed staggered continuously rotating and intermittently oscillating perforated cylinders, delivery members extending axially of said cylinders and comprising chutes
55 pivotally supported at one end beneath said cylinders and extending towards the oppositely disposed lower cylinder and into the interior thereof, and means carried by said cylinders for supporting the free end of said chutes relatively to the axis of the cylinders themselves.
13. In a machine of the character de-
scribed, the combination of oppositely dis-
posed staggered continuously rotating and
60 intermittently oscillating perforated cylindrical sieves, said sieves being arranged in two series so that alternate sieves are super-
posed one above the other, operating means for said sieves including vertically super-
posed bevel gears mounted intermediate said opposed cylindrical sieves, and means for
65 rotating said bevel gears in opposite direc-
tions whereby the rotation of each of said sieves will be in the same direction.
14. In a machine of the character de-
scribed, the combination of sorting stations
70 disposed in parallel vertical series at oppo-
site sides of the machine, one station mounted
above the other in staggered relation;
operating means for said stations including
continuously rotating bevel gears, one di-
75 rectly above the other, and complementary
bevel gears at said stations and adapted to
mesh with said first named bevel gears.
15. In a machine of the character de-
scribed, the combination with a plurality
80 of staggered sorting stations arranged one
above the other at opposite sides of the ma-
chine, of intermittently oscillating and
continuously revolving perforated cylindri-
85 cal sieves carried by each station and pro-
vided with graduated perforations in suc-
ceeding cylinders, whereby successive sepa-
90 ration of various sizes of material may be
effected.
16. In a machine of the character de-
scribed, the combination of a series of sort-
95 ing stations alternate members of said sta-
tions being disposed in opposite directions
and toward opposite sides of the machine,
feeding mechanism for feeding charges of
material to one end of said series of sort-
105 ing stations, and oscillating guiding means
mounted in said machine whereby said
charge of material may be guided after suc-
cessive separations from below one sorting
station to the interior of the succeeding
110 lower station of the series.
17. In a sorting machine, a plurality of
120 staggered sorting stations comprising oscil-
lating and rotating cylindrical screens, a
series of adjustable cams for operating said
stations, an intermittently operated feed-
125 ing mechanism for feeding subsequent
130

- charges of material to be sorted to said sorting stations, means for operating said feeding mechanism, and operating means cooperating with said cams to automatically engage and disengage said first named means.
18. In a sorting machine, a plurality of sorting stations arranged one above the other at alternate sides of the machine, feeding mechanism including a hopper mounted in said machine, a screw conveyor, and clutch mechanism for intermittently operating said screw conveyor to discharge subsequent charges of material from said hopper to the uppermost sorting station.
19. In a sorting machine, a plurality of sorting stations arranged one above the other at alternate sides of the machine, feeding mechanism including a hopper mounted in said machine, a communicating passage from said hopper to the uppermost sorting station, a screw conveyor mounted in said passage and adapted to move material from said hopper toward the uppermost sorting station, adjustable means for tilting said stations, and clutch mechanism effecting the operation of said conveyor screw at certain inclinations of said sorting stations.
20. In a sorting machine, a plurality of alternately opposed perforated cylinders arranged one above the other, supporting frames pivotally supported in vertical alignment one above the other and intermediate the opposing cylinders, rotary driving means mounted axially of the pivots of said supporting members, and adapted to operate said cylinders, cams for raising and lowering the free ends of said frames, and receptacles adjacent the free ends of said frames for receiving the contents of said cylinders when the latter are inclined toward the receptacles by the operation of said cams.
21. In a machine for sorting material according to size, the combination with a plurality of cylindrical sieves, of supporting means for said sieves including pivoted arms, the outer end of each arm being provided with an arcuately adjustable bearing having a square pivoted end portion, and a spring secured at one end to said arm and extending towards said pivoted bearing to yieldably engage the square surface of the pivoted end portion whereby the bearing may be held in open or closed position.
22. In a machine for sorting material according to size, the combination with a plurality of sorting stations, of mechanisms for continuously rotating and intermittently tilting said stations, and driving means for simultaneously and continuously operating said rotating and tilting mechanism whereby alternate members of each mechanism may be rotated in opposite directions.
23. In a sorting device of the character described, the combination of an upright frame having parallel side walls and back wall, sorting stations mounted in zig-zag formation on said back wall, means for tilting said stations toward and away from each other, a chute pivotally supported below each sorting station and extending axially of the latter into the interior of the succeeding lower station, means for imparting relative arcuate movement to said chute during the tilting movement of said station, and a shield carried by said station closely adjacent the pivoted end of said chute, whereby the space between the latter and said station may be closed during relative movement of the two members.
24. In a sorting device of the character described, the combination of a series of troughs for delivering unsorted material from one side of the device to the other side thereof, said troughs being located one above the other and extending in opposite directions, pivoted supports for said troughs, and means movable relatively to said troughs whereby one end of the latter may be enclosed.
25. In a sorting device of the character described, the combination of a series of sorting stations comprising cylinders provided with perforations therein, means for tilting said cylinders to discharge their contents, and receptacles removably supported in said device and located at the rear of said cylinders, said receptacles comprising a box having an inclined receiving lip extending beneath the end of said cylinder and adapted to be engaged by the downward movement of said cylinder during tilting movement of the latter, whereby the contents of said cylinder may be released to fall onto said lip.
26. In a sorting device of the character described, the combination with a plurality of constantly rotating cylindrical sieves adapted to successively separate various sizes of material, of pivoted supporting apparatus for said cylinders, and resilient means carried by said apparatus and extending longitudinally of said cylinders, conforming to the arc of said sieves and in engagement with the outer periphery thereof, whereby material caught in the mesh of said sieves may be returned to the interior of said cylinders.

In testimony whereof I affix my signature.

CHARLES F. RICHARDSON.
